UNITED STATES PATENT OFFICE.

EDWARD C. ABEL, OF NEW YORK, N. Y.

DESIGN FOR A STONE SETTING FOR FINGER-RINGS OR SIMILAR ARTICLES.

41,963.

Specification for Design.

Patented Dec. 12, 1911.

Application filed June 26, 1911. Serial No. 635,483. Term of patent 14 years.

To all whom it may concern:

Be it known that I, EDWARD C. ABEL, a citizen of the United States, residing at New York, in the county of Queens and State of New York, have invented a new, original, and ornamental Design for Stone Settings for Finger-Rings or Similar Articles, of which the following is a specification, reference being had to the accompanying drawing, forming part thereof.

In the accompanying drawing, Figure 1

is a side view; and Fig. 2 a face view showing my new design.

I claim:

The ornamental design for a stone setting for finger rings, or similar articles as shown.

EDWARD C. ABEL.

Witnesses:

C. E. MULREANY,
FRANK G. AT LEE.
